UNITED STATES PATENT OFFICE.

GEORGE HARRISON BLOCK, OF HANNA, ALBERTA, CANADA, ASSIGNOR OF THIRTY-FIVE ONE-HUNDREDTHS TO SAYLE ALLEN BROWN, OF HANNA, ALBERTA, CANADA.

REVOLVING SELF-CLEANING MOLDBOARD PLOW.

Application filed February 19, 1923. Serial No. 620,068.

To all whom it may concern:

Be it known that I, GEORGE HARRISON BLOCK, a British subject, and a resident of the Postal District of Hanna, in the Province of Alberta, Dominion of Canada, have invented certain new and useful Improvements in a Revolving Self-Cleaning Moldboard Plow, of which the following is a specification.

10 This invention relates to revolving self-cleaning mold board structures for plows.

An object of the invention resides in providing a plow structure wherein suitable means are provided for rotatably mounting 15 a disc mold board, for cooperation with a share carried thereby.

Another object of the invention resides in providing a plow structure wherein a casing of suitable shape is provided on the lower 20 forwardly curved end of the plow beam, and mounting a share at the forward end thereof and a shaft for rotation in a horizontal plane provided with bearings in the central portion of the casing, for mounting a disc 25 member for rotation which is adapted to form a rotatable mold board, adapted to discharge the earth broken by the share.

The invention includes other objects and 30 improvements in the details of construction and arrangement of the parts which are more particularly pointed out in the following description and claim, directed to a preferred form of the invention, it being understood, however, that various changes 35 in the size, shape and construction of these parts may be made, without departing from the spirit and scope of the invention as described and claimed.

In the drawing, forming a part of this 40 application:

Figure 1 is a perspective view of the improved plow construction, having a rotatable mold board.

Figure 2 is a vertical transverse section 45 through the structure shown in Figure 1.

1 indicates the rear downwardly and forwardly curved end of a plow beam, on which is mounted a casing 2, having a vertical wall 3, on the land side of the beam, tapering 50 downwardly and forwardly to the forward end, and terminating in substantially a point with the bottom wall 4 thereof, which extends laterally and inclines slightly downwardly from the lower edge of said vertical wall 3, as shown in Figure 2, the outer edge

of the bottom wall 4 being inclined forwardly and terminating in a point with the forward end of the vertical wall 3, the casing having a sloping wall 5, of a somewhat concaved form, joining the upper inclined 60 edge of the vertical wall 3, and the outer inclined edge of the bottom wall 4. It will be seen from this construction that the casing is of substantially triangular cross section and of substantially uniformly reducing size from the rear to the forward end, 65 where it terminates in substantially a point, over which is mounted the plow share 6 of usual construction, which is bolted to the sloping wall, as indicated at 7, and which is 70 provided with a vertical extension 8, of usual construction, extending along the outside of the forward end of the vertical wall 3.

A bearing 9 is mounted in the central portion of the sloping wall 5, for rotatably 75 mounting a shaft 10, which projects through the casing, and has one free end seated in a bearing 11, mounted on the vertical wall 3, in horizontal alignment with the bearing 9, so that the shaft 10 normally rotates in a 80 horizontal plane. The other free end of the shaft 10 extends beyond the sloping wall 5 of the casing, and carries a concaved disc element 12, which forms a revolving mold board, and on the rear side of which is carried a sprocket 13, surrounding the shaft 10, for receiving a suitable drive chain from a source of power by which the mold board is rotated. The lower edge of the disc 12 projects in the rear of and below the upper free 85 edge 14 of the plow share 6, so that as the furrow is opened by the share, the dirt will be directed upwardly against the revolving mold board, which will effect the turning of the furrow away from the plow, in a well 90 known manner.

A suitable form of scraping device is indicated at 15, for cleaning the surface of the disc 12, which is mounted in a suitable manner on the casing 2 through the medium 95 of a bracket 16.

From the above description it will be seen that the casing structure 2 in mounting the shaft 10 in the bearings 9 and 11 will have the torsional strain directed thereto, when 100 the plow is in use, distributed throughout the sloping and vertical walls of the casing which are maintained in rigid relation through the bottom walls. This provides a rigid mounting structure for the disc, so 105 110

that the same will be maintained in operative relation and condition on the casing, although subjected to rough usage. In addition, the casing 2 can be readily attached to the plow beam, by posts or the like, the heads of which are protected thereby, in order that the same may be readily removed for replacement or repair, the casing being of simple construction, and therefore can be manufactured at a relatively small cost.

What is claimed is:

A revolving mold board plow structure including a casing rigidly mounted on the depending, forwardly curved end of a plow beam, said casing having a vertical wall on the land side of the beam, the upper edge of which inclines downwardly and forwardly, a bottom wall extending laterally and inclining slightly downwardly from the vertical wall, and having the free edge inclined forwardly toward said vertical wall, and termi-

nating in a forward substantially pointed end therewith, and a sloping wall connecting the upper edge of the vertical wall, and the outer edge of the bottom wall, a share 25 mounted on said casing and secured to the sloping and vertical walls thereof, shaft bearings mounted in the sloping and vertical walls respectively, in horizontal alignment, a shaft rotatable in said bearings, a disc member 30 forming a mold board mounted on the outer end of said shaft, adjacent said sloping wall for rotation therewith, the lower portion of said disc extending in the rear of the upper edge of said shaft, and a 35 sprocket mounted on the shaft for receiving a drive chain for rotating said shaft and disc, the bearings being carried in spaced relation by the sloping and vertical walls of the casing, serving to distribute the torsional strains 40 from the shaft throughout the casing.

GEORGE HARRISON BLOCK.
